(57) **CLAIM**

The ornamental design for a structural post for a screen enclosure, as shown and described.

DESCRIPTION

FIG. 1 is a perspective view illustrating my design for a structural post for a screen enclosure.

FIG. 2 is a top end view thereof.

FIG. 3 is a bottom end view thereof.

FIG. 4 is a front view thereof.

FIG. 5 is a right side view thereof.

FIG. 6 is a rear view thereof.

FIG. 7 is a left side view thereof; and,

FIG. 8 is another perspective view with environmental subject matter.

The broken lines representing circular holes shown in FIGS. 1, 4, 6, and 8 illustrate portions of the structural post for a screen enclosure that form no part of the claimed design. The additional broken lines shown in FIG. 8 represent environment. The break lines shown in the center of the beam indicate a symbolic break in length. The appearance of any portion of the article between the break lines forms no part of the claimed design.
